GIUSEPPE M. BELLANCA, OF NEW CASTLE, DELAWARE

EXHAUST MANIFOLD

Application filed February 21, 1930. Serial No. 430,379.

This invention relates to the construction and mounting of an exhaust manifold for aeronautical engines.

In the development of airplanes in connection with which engines of the radial and other more or less similar types are used, considerable difficulty has been found in so mounting the exhaust manifold that it will not present a substantial surface area to produce air resistance and a corresponding restriction in speed of flight of the airplane. This difficulty arises out of the necessity for mounting the exhaust manifold outside the chamber formed by the shell of the fuselage and in a disposition substantially encircling the cowl portion of the fuselage transversely to the direction of flight. The manifold by thus extending across the line of flight, presents its forward surface throughout its length to the resistance of the air.

It has also been found that when the exhaust manifold is mounted to the rear of the engine cylinders, as is ordinarily done, hot "spots" develop along the manifold opposite each of the cylinders. This is due to the fact that the cylinders shield these "spots" from the full effect of the cooling air and that some of the heat from the cylinders themselves is transmitted to the manifold at these points.

A general object of the present invention is to provide an exhaust manifold for radial aeronautical engines which will be free from the objectionable features referred to and which will provide a minimum amount of air resistance.

Further objects of the invention are to minimize the effects of the noise produced by the discharging exhaust, to prevent overheating of the manifold either wholly or in spots, and to prevent buckling or distortion of the parts under expansion effects arising out of temperature changes.

The invention includes the mounting of the exhaust manifold in a recess or channel formed in the surface of the engine cowling, the manifold being thereby partly or wholly protected from engagement of the rushing air therewith.

Another feature of the invention is the mounting of the manifold in a spaced apart relation to the surface of the receiving channel so that air can flow through the space between the manifold and channel surface to produce a cooling effect on the manifold and prevent overheating thereof.

Another feature of the invention is that the manifold is allowed to project slightly outside of the surface of the cowling so as to intercept a part of the air current and direct it through the space between the manifold and the channel surface.

Another feature of the invention resides in the positioning of the manifold to the fore of the engine cylinders instead of to the rear in order to avoid heat "spots" on the manifold.

Another feature of the invention resides in the provision of an exhaust manifold having a formation in cross-section such as will provide a minimum air-resistance area.

Another feature of the invention resides in the use of flexible joints in the manifold structure to prevent injury to the parts by expansion and contraction effects.

Still another feature of the invention resides in an adaptability of the manifold structure to be mounted in various positions to cause the exhaust to be discharged at any desired point in the length of the manifold structure.

Other features of the invention will be hereinafter referred to.

In the drawings, in which a preferred embodiment of the invention has been selected for illustration,

Figure 1 is a diagrammatic view showing a portion of the forward end of an airplane equipped with an exhaust manifold construction embodying the invention.

Figure 2 is a sectional view on an enlarged scale taken on the line 2-2 of Figure 1.

Figure 3 is a detail perspective view of the telescoping expansion joint employed in my improved manifold.

Figure 4 is a detail perspective view of the flexible joint employed in the branches of my improved manifold.

Figure 5 is a sectional view of a modification of Figure 2.

Referring to the drawings for a more detailed description of the invention, at 10 is shown the engine cowling portion of the fuselage of an airplane through openings 11 in which the cylinders 12 of an engine of the radial type protrude. The forward portion of the cowling 10 is equipped with a cap member or fairing 13 designated to decrease the effect of air resistance acting on the hub portions of the propeller 14.

In order to dispose of the exhaust from the radially disposed cylinders 12 through a common discharge conduit an exhaust manifold 15 is made use of which is disposed in a substantially encircling relation to the cowling structure 10, the location of the manifold being just to the fore of the positions of the engine cylinders 12. Branches 8 are provided at intervals along the exhaust manifold 15 for the purpose of receiving into the manifold the exhaust from the respective cylinders. Each of these branches is joined to a pipe connection 16 by a flexible joint 22, shown in detail in Figure 4. One the free end of each of the pipe connections 16 is provided a coupling member 7 whereby members 16 are tightly secured to the discharge ports 17.

In order to provide for expansion or contraction of the manifold structure itself under changing temperature conditions, a telescopic joint 25, such as is shown in Figure 3, is provided, which permits of relative movement of the contiguous sections of the manifold toward or from each other to thereby prevent distortion or other injury to the manifold by the expansion and contraction effects due to changes in temperature.

In order to cause the manifold to present a minimum area of surface to prevent air resistance the manifold is mounted in a recess or groove 19 formed in the outer surface of the engine cowling 10. The groove or recess 19 extends circumferentially around the entire surface of the cowling and the disposition of the groove provides for the mounting of the manifold 15 in any desired angular relation to the cowling so as to cause the discharge member 18 to be located at the most convenient point. In Figure 1 of the drawings the discharge member 18 of the manifold is shown disposed beneath the floor wall of the fuselage, this location of the discharge terminal being useful in overcoming the effect of noises produced by the exhaust on the occupants of the compartments in the fuselage. It will be clear that the manifold 15 may be rotatably adjusted within the groove 19 to cause the terminal discharging member 18 to be disposed along either side of the fuselage or at a point to discharge above the fuselage and the supporting wing or plane.

In order to prevent overheating of the

manifold and the communication of heat to the adjacent surface of the cowling 10, the manifold 15 is so mounted that its inner wall 29 is slightly spaced apart from the adjacent surface of the groove or recess 19 as is clearly shown in Figure 2 of the drawings. The space 20 which is thus formed provides a passageway through which air can flow, as is indicated by the arrows in Figure 2 of the drawings, to thereby dissipate heat and prevent overheating of the adjacent parts. In order to facilitate the rush of air through the passageway 20 formed between the manifold 15 and the surface of the groove 19 the forward or leading edge 30 of the manifold is caused to protrude slightly beyond the adjacent outer surface of the cowling 10 to thereby function to provide a scooping action on the air stream rushing rearwardly along the surface of the cowling 10. The air thus caught or entrapped is diverted through the channel 20 as will be seen and produces the cooling effect referred to.

It will also be noted that the cross-section or formation of the manifold member 15 is such as to present a minimum degree of resistance to the air. In the drawings it will be noted that the manifold has the formation of a flattened tube with forwardly and rearwardly extending angles and a substantially flat outer surface 21 following approximately the contour of the outer surface of the cowling 10. While this particular formation has been found effective in practice it will be apparent that other formations of the manifold cross-section may be employed with useful results.

Another feature of the invention resides in the use of flexible or yielding coupling elements in the body structure of the manifold member and also in the pipes 16 through which connections are made between the manifold and the engine cylinders 12. Coupling members or joints 22 are provided in the pipe connections 16 for the purpose. These coupling members may take the form of split sleeves an example of which is shown in Figure 4 of the drawings, the sleeve being provided with a clamping bolt 23 and having suitable corrugations 24 to prevent slipping of the coupling member from engagement with the joint sections of the exhaust pipes 16 and the branches 8.

In certain types of construction it is possible that the addition of the exhaust manifold of my invention may interfere with the application and removal of the material of cowling structure. To obviate this difficulty the construction indicated in Figure 5 may be used. In this embodiment the cowling 10 of Figures 1 and 2 may be cut into portions. For instance, a nose portion 26 may be provided, cooperating with a recess portion 27, in the recess of which the exhaust manifold 15 may be positioned. The manifold may be spaced

away from the member 27 by a small distance as before to provide the passageway 20 for cooling air. This construction permits the ready removal of the nose portion of the cowl for access to the engine members, or of the rear portion, or of the manifold and grooved portion together.

As a further modification the cowl member may be separated at two points as shown 10 in Figure 5 to provide a nose portion 26, a channel portion 27 and a rear portion 28. This construction permits the removal of the nose portion and the rear portion of the cowl independently of the exhaust manifold and 15 of the recess portion. This modification of the construction provides means for a more convenient and easy access to the engine structures.

It will be seen that a manifold structure 20 and a method of mounting the same have been provided which overcomes or obviates the air resistance effects which are ordinarily encountered in the use of a manifold structure which must be disposed transversely to the 25 line of flight of the airplane on which it is carried.

The language and expressions which have been employed throughout the specification 30 are used as terms of description only and not of limitation, and such terms are intended to include all the equivalents and such modifications as are possible to be employed within the scope of the invention claimed.

I claim:

35 In an airplane having an engine and propeller at its forward end, a stream lined cowl for enclosing the major part of said engine, said cowl having a circumscribing groove formed in its surface between said engine and 40 propeller, and a stream lined exhaust manifold nested within said groove, spaced therefrom and formed so that its outer surface forms a substantial continuation of the surface of said cowl, said manifold having its 45 forward edge projecting slightly outside the surface of said cowl so as to deflect an air current into the space between said cowl and said manifold.

50 In testimony whereof I affix my signature.
GIUSEPPE M. BELLANCA.
